INJECTION PUMP

Jean Mercier, Paris, France

Application May 8, 1941, Serial No. 392,579

13 Claims. (Cl. 103—37)

The present invention relates to fuel injection pumps.

An object of the invention is to provide a pump of this type in which leakage around the piston during the injection stroke is practically eliminated.

Another object of the invention is to provide a fuel injection pump in which the piston is already travelling with a high velocity when the injection of fuel is started, that is to say when the discharge valve opens.

Still another object of the invention is to provide an injection pump in which the discharge pipe is opened as suddenly as possible, which corresponds to a very sharp rise of the pressure in the pump barrel.

Still another object of the invention is to provide a pump of the type above mentioned with means for accurately controlling the end of the injection, said end being also as sudden as possible.

With these, and other, objects in view, according to an essential feature of the invention, I provide, in permanent communication with the portion of the pump barrel located between the piston and the discharge valve, a chamber of variable volume and means for controlling the volume of said chamber so as to permit its free increase during at least one portion of the stroke of the piston and, on the contrary, to prevent said increase during another portion of said stroke.

Other features of the present invention will result from the following detailed description of some specific embodiments thereof.

Preferred embodiments of the present invention will be hereinafter described, with reference to the accompanying drawings, given merely by way of example and in which:

Fig. 1 is a diagrammatic sectional view of a pump made according to a first embodiment of the invention;

Fig. 2 is a view, similar to Fig. 1, showing the same pump with the parts in different relative positions;

Fig. 3 is a diagrammatic axial section of another embodiment of pump according to the invention including a snap-action release mechanism S;

Fig. 4 is a transverse section of this mechanism S;

Fig. 5 is a partial view showing said mechanism from the same view point as in Fig. 3, but after it has snapped open;

Fig. 6 is a diagrammatic axial section, similar

to Figs. 1 and 3, showing a modification of the embodiment of Fig. 3;

Fig. 7 is a similar view, showing still another embodiment.

As shown by the drawings, the pump according to the invention includes a pump body 1 provided with a cylindrical bore 2 forming the pump barrel. In this pump barrel 2 is slidably mounted the piston 3 of the pump, actuated in any suitable manner.

For instance, in the embodiment shown by Figs. 1 and 2, the lower end of piston 3 cooperates with a roller 61, carried by a lever 62 pivoted at 63. This roller 61 is further subjected to the action of a push-piece 64, urged upwardly by a spring 65 interposed between said push-piece and the bottom of casing 60, which is rigid with frame 1.

Piston 3 is further urged in the downward direction with a spring 5 bearing against frame 1.

The movement of lever 62 is produced by a cam 4, turning about an axis 67 and cooperating with a roller 68 provided at the end of lever 62.

At the top of the pump barrel 2, is provided the discharge conduit 6, controlled by the spring loaded discharge valve 7.

An inlet conduit 8 opens into an annular inlet port provided in the cylindrical inner wall of the pump barrel.

Body 1 is further provided with a cylindrical chamber 10, in permanent communication with the pump barrel 2. In this chamber 10 is slidably mounted a piston 11.

An adjustable stop piece 12 is carried by the frame 1 of the system so that it can occupy any desired position (within given limits) along the common axis of chamber 10 and piston 11. For instance this piece 12 carries a worm 13 in mesh with a rack 14, guided with respect to body 1.

I can thus control the point at which the downward stroke of piston 11 is suddenly stopped by its contact with piece 12.

In order to ensure the return of piston 11 to its upper position, a return spring 15 is interposed between the upper end of piston 11, and a plunger 16 fixed to the frame of the pump through a nut 17.

This pump will work in the following manner: The downward stroke of piston 3 takes place under the action of spring 5 when roller 61 is moving downwardly as the result of the motion imparted to lever 62 by cam 4, and against the action of spring 65.

During this downward stroke, piston 3 draws

in liquid into barrel 2 through conduit 8 and port 9.

Then roller 68 comes to run beyond the point 4¹ of the outline of cam 4, which permits lever 62 to pivot upwardly under the effect of push-piece 64 and spring 65. This upward pivoting movement of lever 62 corresponds to an upward stroke of piston 3.

In the course of this upward stroke, the upper edge of piston 3 comes to the level of the upper edge of port 9 (position shown by Fig. 1). The portion of the pump barrel 2 above piston 3, and the chamber 10, above piston 11, which communicates with said pump barrel, are now filled with liquid which, in the course of the remainder of the upward stroke of piston 3, can escape to the outside only through discharge pipe 6, past valve 7, this discharge taking place when the pressure in barrel 2 suddenly rises and overcomes the resistance of spring loaded valves 7.

But, for a certain time after piston 3 has moved upwardly beyond the position illustrated by Fig. 1, the pressure in barrel 2 does not rise, because piston 11 is simultaneously moving downwardly in cylinder 10 so that the total volume of chambers 2 and 10 does not tend to decrease.

Piston 3 thus comes to the position illustrated by Fig. 2, where it has considerably overlapped port 9, and which corresponds to the lower end of piston 11 striking stop piece 12 and being suddenly immobilized by its contact with said top piece.

As piston 3, under the action of cam 4, keeps moving at high speed, there is a very sudden rise of pressure in chamber 2, which causes valve 7 to open practically instantaneously, whereby injection starts in a very sharp manner.

As the top edge of piston 3 is now at a considerable distance beyond the top edge of port 9, no danger of liquid leaking back to said port toward the inlet conduit 8 can occur.

The end of the injection takes place when an abutment 69, provided at the lower end of piston 3 comes into contact with a shoulder 70, provided on casing 60. Then, as roller 68 has now run along cam 4 beyond point 4¹, lever 62 moves downwardly and piston 3 follows its movement under the action of spring 5.

The annular groove 9 corresponding to the inlet port in the pump barrel is in communication with another annular groove 18 provided in the inner wall of cylindrical bore 10, so that, if liquid leaks along said wall, it returns to the inlet circuit, and further prevents the inflow of air during the suction stroke.

According to an important feature of the invention, I can determine the end of the injection by controlling the displacement of piston 11. For instance, this piston being supposed to be fixed in position during the injection, is suddenly allowed to move freely when it is desired to stop the injection, so that the pressure drop thus produced in the pump barrel causes valve 7 to close.

Embodiments of mechanisms adapted to produce this operation are shown by Figs. 3 to 7.

In these embodiments of pumps according to the invention, the beginning of the cycle of operation is supposed to be the same as above described with reference to Fig. 1.

For instance, in the embodiment of Figs. 3 to 5, the stopping of the downward movement of piston 11 is produced by the contact of a rod 20, carried by this piston, with a stop piece 21, slidably guided in the vertical direction with respect to body 1.

Stop piece 21 can occupy either of two positions, to wit its upper position, shown by Fig. 3, in which it is held by the snap action mechanism S, interposed between fixed spindle A and piece 21, and its lower position, shown by Fig. 5, in which mechanism S has snapped into broken position under the action of the shoulder 22 of piston 3 coming into contact with projection 23 of said mechanism S.

As shown by Figs. 3, 4 and 5, mechanism S is constituted by a kind of knuckle including two branches 24 and 25, pivoted to each other about spindle 27, and having their movement with respect to each other stopped in one direction (in a position which corresponds to said branches being in line with each other and thus holding piece 21 in its upper position) by respective abutments bearing against each other along line 28. Branch 24 is pivoted to piece 21 about spindle 26, while branch 25 is pivoted about spindle A. When the above mentioned abutments of branches 24 and 25 are applied against each other (along line 28), spindle 27 is located in the plane of spindles 26 and A, and the whole is resiliently held in this position by a spring 29 interposed between an element of body 1 and a lever 30 carried by branch 25. It will be readily understood that as soon as the contact of the shoulder 22 of piston 3 with projection 23, carried by branch 25, has caused said branch to pivot so that spindle 27 is now located on the right hand side of the plane of spindles 26 and A, the knuckle joint is broken and snaps open, the downward thrust on piece 21 being opposed merely by the action of spring 29, which is very small with respect to thrust.

Therefore piston 11 is suddenly allowed to move downwardly, the pressure drops in barrel 2, valve 7 closes and the injection is suddenly stopped.

The point at which this action takes place can be determined at will by making spindle A adjustable vertically with respect to the pump body 1.

In this case, a vertical displacement of spindle A modifies both the beginning and the end of the injection period. In order to permit of modifying only the end of this period, the shoulder 22 of the main piston 3 is made of helical shape, so that, by turning piston 3 about its axis, I can vary the time at which projection 23 is struck by said shoulder 22.

In the modification illustrated by Fig. 6, piston 11 is stopped in its downward movement by the contact of its bevelled lower edge 35 with balls 36 mounted in radial holes 37 provided in a piece 38 adjustably fixed with respect to the body 1 of the pump.

A movable piece, movable vertically together with piston 3, is provided with an annular space 40 into which balls 36 can penetrate when said recesses come opposite holes 37.

In the course of this radial movement, said balls come to be tangent to the cylindrical wall of an annular recess 41 provided in piece 38 and corresponding in shape and size to the outer cylindrical wall of piston 11. Therefore, this piston can now freely move down in said space 41, which, as above explained, immediately produces the end of the injection.

Finally, in the embodiment of Fig. 7, the stop piece 51 against which piston 11 strikes for producing the beginning of the injection has its vertical position determined by a roller 44 carried by a lever 43, pivoted at 42 and controlled by a cam 45. This cam is circular over a portion of its periphery, whereby roller 44, and consequently

piece 51 are held in the fixed upper position for a portion of the rotation of said cam. When the end of lever 43 comes on the non-circular, and projecting, portion of cam 45, this lever is suddenly pivoted downwardly, thus bringing roller 44, and consequently piece 51, in the lower position, so that piston 11 can slide freely in the downward direction and the pump injection is stopped. A spring 49 keeps lever 43 applied against cam 45. Cam 45 also acts on a lever 47, pivoted at 46 and the other end of which is fitted with a roller 48 which controls the vertical displacements of the main piston 3. The latter is urged in the downward direction by a spring 52.

The position of point 42, about which lever 43 is pivoted can be adjusted from the outside by means of hand wheel 53.

It will be noted that the movement of roller 44, which constitutes the movable abutment which is to coact with auxiliary piston 11, is produced by a cam 45 which imperatively pushes lever 43 downwardly when said auxiliary piston is to be released. At first sight it would seem simpler to obtain this movement by means of a cam which would keep lever 43 in an upward position and which, at the desired time, would allow this lever to pivot downwardly. But the disadvantage of this system would lie in the necessity of employing a cam having an outline including first a circular portion and then a portion of decreasing diameter forming an external angle with the circular portion.

On the contrary, in the device according to the invention, cam 45 is so shaped that after a circular portion there is a portion projecting with respect thereto, the whole forming an internal angle at 45a. Now this arrangement is particularly advantageous because the sudden downward displacement of the roller carried by the end of roller 43, which runs on cam 45, when this last mentioned roller comes onto the non-circular portion of said cam 45, corresponds exactly to the outline of the cam. As a matter of fact, in an arrangement of this kind (in which the cam outline forms an internal angle), the center of the last mentioned roller describes a curve which is exactly parallel to the outline of the cam and which, therefore, reproduces the angle in question, whereas, if the cam made an external angle, the trajectory of the center of said roller would include two curvilinear elements parallel to the corresponding elements of the outline of the cam which constitutes the sides of this external angle, but joined to each other by a circular arc instead of forming a sharp angle which would prevent the sudden movement of the lever, which is to be obtained owing to the sharp angle provided in the cam outline.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

What I claim is:

1. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said

discharge valve, a piston slidable in said cylinder, so as to form, in said cylinder, a variable volume chamber communicating with said portion of the pump barrel, means for locking said second piston with respect to its cylinder so as to keep the volume of said chamber constant, during the injection and means for suddenly releasing said second piston to permit free increase of the volume of said chamber, whereby the pressure drops suddenly in said pump barrel and stops injection.

2. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, so as to form, in said cylinder, a variable volume chamber communicating with said portion of the pump barrel, means for locking said second piston with respect to its cylinder so as to keep the volume of said chamber constant during the injection, and means adapted to act in synchronism with the movement of said first piston for suddenly releasing said second piston to permit free increase of the volume of said chamber, whereby the pressure drops suddenly in said pump barrel and stops injection.

3. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, so as to form, in said cylinder, a variable volume chamber communicating with said portion of the pump barrel, means for locking said second piston with respect to its cylinder so as to keep the volume of said chamber constant during the injection, and adjustable means adapted to act in synchronism with the movement of said first piston for suddenly releasing said second piston to permit free increase of the volume of said chamber, whereby the pressure drops suddenly in said pump barrel and stops injection.

4. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, so as to form, in said cylinder, a variable volume chamber communicating with said portion of the pump barrel, means for locking said second piston with respect to its cylinder so as to keep the volume of said chamber constant during the injection and means operative by said piston for suddenly releasing said second piston to permit free increase of the volume of said chamber, whereby the pressure drops suddenly in said pump barrel and stops injection.

5. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said

discharge valve, a piston slidable in said cylinder, so as to form, in said cylinder, a variable volume chamber communicating with said portion of the pump barrel, means for locking said second piston with respect to its cylinder so as to keep the volume of said chamber constant during the injection and adjustable means operative by said piston for suddenly releasing said second piston to permit free increase of the volume of said chamber, whereby the pressure drops suddenly in said pump barrel and stops injection.

6. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, so as to form, in said cylinder, a variable volume chamber communicating with said portion of the pump barrel, a stop piece adapted to cooperate with said second piston for fixing it with respect to its cylinder so as to keep the volume of said chamber constant during the injection, said stop piece being retractable with respect to said second piston substantially in the direction of the axis thereof, and means adapted to act in synchronism with the movement of said first piston, and means for suddenly retracting said stop piece to release said piston and to permit free increase of the volume of said chamber, whereby the pressure drops suddenly in said pump barrel and stops injection.

7. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, so as to form, in said cylinder, a variable volume chamber communicating with said portion of the pump barrel, a stop piece adapted to cooperate with said second piston for fixing it with respect to its cylinder so as to keep the volume of said chamber constant during the injection, said stop piece being retractable with respect to said second piston, retracting means for moving said stop piece so as to release said second piston and to permit free increase of the volume of said chamber, whereby the pressure drops suddenly in said pump barrel and stops injection and a single cam means for controlling the movement of said second piston and of said retracting means.

8. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, so as to form, in said cylinder, a variable volume chamber communicating with said portion of the pump barrel, abutment means adapted to cooperate with said second piston for fixing it with respect to its cylinder so as to keep the volume of said chamber constant during the injection, said abutment means being retractable with respect to said second piston in a direction transverse to the axis thereof, and means adapted to act in synchronism with the movement of said

5 first piston for suddenly retracting said abutment means to release said piston and to permit free increase of the volume of said chamber, whereby the pressure drops suddenly in said pump barrel and stops injection.

9. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, a variable volume chamber communicating with said portion of the pump barrel, a stationary sleeve coaxial with said second piston provided with radial holes, abutment balls in said holes adapted to cooperate with said second piston for fixing it with respect to its cylinder so as to keep the volume of said chamber constant during the injection, said balls being retractable with respect to said second piston by radial outward movement in said holes, and a second sleeve surrounding the first and adapted to slide axially with respect thereto in synchronism with the movement of said first piston, provided with recesses adapted to come into register with said holes for suddenly causing said balls to retract into said recesses so as to release said piston and to permit free increase of the volume of said chamber, whereby the pressure drops suddenly in said pump barrel and stops injection.

10. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, a variable volume chamber communicating with said portion of the pump barrel, an abutment piece adapted to cooperate with said second piston for fixing it with respect to its cylinder so as to keep the volume of said chamber constant during the injection, said abutment means being retractable with respect to said second piston and a snap action mechanism interposed between a fixed point and said stop piece for holding the latter, for a time, in fixed position with respect to said cylinder and adapted to act in synchronism with the movement of said first piston, for suddenly retracting said abutment piece to release said piston and to permit free increase of the volume of said chamber, whereby the pressure drops suddenly in said pump barrel and stops injection.

11. An injection pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slidable in said cylinder, so as to form, in said cylinder, a variable volume chamber communicating with said portion of the pump barrel, an abutment piece adapted to cooperate with said second piston for fixing it with respect to its cylinder so as to keep the volume of said chamber constant during the injection, said abutment means being retractable with respect to said second piston, an adjustable knuckle joint interposed between a fixed point and said stop

piece for holding the latter, for a time, in fixed position with respect to said cylinder and means carried by said first piston, for snapping said knuckle and causing it suddenly to retract said abutment piece to release said piston and to permit free increase of the volume of said chamber, whereby the pressure drops suddenly in said pump barrel and stops injection.

12. An injecting pump which comprises, in combination, a pump barrel, liquid inlet means connected to said pump barrel, a piston movable in said pump barrel, a spring loaded discharge valve connected with said pump barrel, a cylinder in permanent communication with the portion of said pump barrel between said piston and said discharge valve, a piston slideable in said cylinder, so as to be free to move in said cylinder in response to the movement of the first piston for a portion of its stroke toward the discharge valve,

after the closing of said inlet means, without the pressure rising in said pump barrel, means for suddenly stopping this movement of the second mentioned piston whereby the pressure rises suddenly in said pump barrel and said discharge valve opens, to produce injection during another portion of the remainder of said stroke, and means for suddenly releasing said second piston to again permit free movement of said second piston in response to the movement of the first piston still another portion of said stroke, whereby the pressure drops suddenly in said pump barrel and stops injection.

13. An injection pump according to claim 12, in which both the means for suddenly stopping the movement of the second piston and means for suddenly releasing it are adjustable.

JEAN MERCIER.
